UNITED STATES PATENT OFFICE.

GEORGE A. MEAD, OF MANSFIELD, OHIO, ASSIGNEE TO THE OHIO BRASS COMPANY,
OF MANSFIELD, OHIO, A CORPORATION OF NEW JERSEY.

ELECTRICALLY-OPERATED TRACK SWITCH.

Original application filed January 3, 1924, Serial No. 684,250. Divided and this application filed July 30, 1925. Serial No. 47,077.

To all whom it may concern:

Be it known that I, GEORGE A. MEAD, a citizen of the United States of America, residing at Mansfield, in the county of Richland and State of Ohio, have invented certain new and useful Improvements in Electrically-Operated Track Switches, of which the following is a specification.

My invention relates to track switches and particularly to electrically and automatically operated track switches under control of the car operator as he approaches the switch.

The object of my invention is to provide a system which can be operated by the car operator by applying the well known principle of "power on" and "power off" the motors and constitutes a division of my copending application Serial No. 684,250, filed January 3, 1924.

My invention resides in the new and novel construction, combination and arrangement of the various electrically operated switches, circuits, etc., hereinafter more fully described and set forth in the drawing accompanying this specification.

In the drawing:

Fig. 1 is a schematic view showing the various circuits usually found in an electrically operated car and which circuits I make use of in the operation of my invention.

Fig. 2 is a schematic drawing showing the arrangement of the various elements making up my invention under normal conditions, that is, just before or just after the system has been operated by a moving vehicle and then returned to its normal condition for further operation, and shows the switch tongue set to the curved position as operated by the coil 5.

Referring to Fig. 1, it is invariably found that electrically operated cars are provided with a current collector W and a trolley pole T connecting the current collector to the car. The car is usually provided with motors M and a controller C for applying "power on" or "power off" the motors at the will of the car operator. The cars are also provided with auxiliary circuits for supplying current to the heaters H, lights L and the air compressor F. The auxiliary circuits are not under the control of the

controller C and, therefore, their current is not only variable, depending on which apparatus is in operation, but the current may be considerable as compared with the current flowing through the motors M and, therefore, I take this fact into account in designing certain elements as herein later described. All apparatus derives its current from the trolley wire through the collector W and through a common ground G or separate grounds, as may be desired. It will be noted that when the operator turns his controller C to the "power on" position that a heavy flow of current will pass through the motors M, but when he turns his controller to the "power off" position no current will flow through the motors M, but current may flow through the apparatus H, L and F. The "power on" and "power off" operation of the controller I make use of for the operation of my invention and I have so arranged my system that with "power on" the motors the switch tongue is automatically set to the curve position and when the controller is set to the "power off" position the switch tongue is automatically set to the "straight ahead" position.

Referring to Fig. 2 I employ a contact pan P provided with two contact members 1 and 2 which are placed adjacent the trolley conductor 3 and which are normally insulated from each other and so arranged that when the current collector W engages the pan P the collector will be out of engagement with the conductor 3. However, when the collector engages the pan P the elements 1 and 2 will be electrically connected. It will also be noted that when the collector W engages the pan P that there is also a path for the current to flow from the contact pan to the ground through the trolley and apparatus H, L and F if in operation, and also through the motors M if the controller is set to "power on". I also employ a track switch A which comprises two solenoids 4 and 5 and having one terminal connected to the ground G through the common conductor 6. The solenoids are provided with a plunger 7 to which a connecting rod 8 is secured which in turn is connected to a track switch tongue 9. When the solenoid 4 is energized the plunger 7 is drawn inwardly and the tongue 9 is

set for the "straight ahead" position and when the solenoid 5 is energized the plunger 7 is drawn outwardly and the switch tongue 9 is set for the "curve" position as shown in

5 Fig. 2.

I also employ an electrically operated switch B which is provided with two coils 10 and 11 and an armature 12 adapted to engage the contacts 13 and 14, but which is 10 normally in engagement with the contact 13. The contact 14 is electrically connected to the remaining terminal of the solenoid 5 by the conductor 15, while the contact 13 is connected to the remaining terminal of the 15 solenoid 4 by the conductor 16 and 17, switch arm 18 and contact 19. It will be evident that when the arm 12 is de-energized and engages the contact 13 with the switch arm 18 is closed, that the solenoid 4 will be 20 energized and the switch tongue thrown to the "straight ahead" position, and if the arm 12 engages the contact 14 the solenoid 5 will be energized and the switch tongue 9 moved to the "curve" position.

25 I also employ an electrically operated switch C provided with operating coils 20 and 21 and an arm 22, also contacts 23 and 25. The switch arm 22 is normally in engagement with the contact 25 and out of 30 engagement with the contact 23. The relation of the contacts to the switch arm are such that the arm 22 will engage the contact 23 before the circuit is broken at the contact 25, at least this engagement will 35 tend to eliminate any arcing at the contact 25 when the circuit is opened at this point.

One terminal of the coil 10 is connected to the contact member 1 by the conductor 26 and the other terminal is connected to the 40 contact 25 by the conductor 27 and the switch arm 22 is normally connected to the trolley conductor 3 by the conductor 28.

45 Interposed between the conductors 26 and 28 is a resistance R and it will be noted that this resistance is normally in shunt with the coil 10, but when the switch C has been energized the conductor 27 is opened at the contact 25 and, therefore, the resistance R is no longer a shunt across the coil 10, but does 50 remain as a connection between the contact member 1 and the trolley conductor 3. The object of the resistance R is to decrease the current which will flow through the coil 10 and, therefore, decrease the current which 55 must be broken by the switch C at the contact 25. The use of the resistance R forms a connection at all times between the pan and the trolley conductor both when the switch C is opened and closed. The winding of the 60 coil 10 is so proportioned that it will operate to pick up the arm 12 when the collector engages the pan with "power on."

65 It will be evident that the energizing of the coil 10 depends upon the drop of potential across the resistance R and, working on

this principle, the current in the coil 10 will be quite small as compared with the current which will flow through the coil 10 if the system was designed to operate without the resistance R and hence the current which 70 must be broken at the contact 25 will be much easier to control than if the system operated without the resistance R.

The coil 10 has its windings so proportioned with respect to the resistance R that 75 when current is flowing through the motors M, the ampere turns will be sufficient to raise the arm 12, but if the current flowing through the resistance R and coil 10 is that due to the auxiliary apparatus H, L and F, 80 the ampere turns of the coil 10 will not be sufficient to raise the arm 12.

When the contact member 2 is energized by being connected with the conductor member 1 through the medium of the collector 85 W the coil 20 will be energized as its terminals are connected to the contact member 2 by the conductor 29, and to the ground by the conductor 30.

When the coil 20 is energized the arm 22 90 will be raised and engage the contact 23 and will break its engagement with the contact 25, but, as already stated, the engagement is preferably not broken at the contact 25 until the engagement is made at contact 23. 95 This, however, is not absolutely necessary as the current broken at the contact 25 is not great when the resistance R is used, but by making simultaneous engagement between the contacts 25 and 23 we are assured of 100 practically eliminating all arcing at the contact 25. The opening of the contact 25 does not open the circuit between the conductor 1 and the conductor 3 as the resistance R, which is preferably of low value, 105 still connects these elements and, therefore, the resistance R and its connections offers a path for the supply of current to the motors of the car should the car come to rest with the collector in engagement with the pan 110 P, otherwise the car would not be able to move on as there would be no connections between the conductor 3 and the contact 1 for the reason that the circuit connected to the contact 25 is open.

115 As soon as the arm 22 is raised and energizes the contact 23, current will flow through the conductor 32, coil 21, and conductor 33 to the arm 12 thereby energizing the same. When the coil 21 is energized it becomes a stick or holding coil for the arm 22 and will maintain the arm 22 in engagement with the contact 23 as long as current is flowing through the solenoids 4 or 5 regardless of whether the collector is in contact with the pan P or has passed beyond the pan.

120 Under these circumstances it is necessary to provide means to open the circuit supplying current to the switch arm 12 in order 125

that the system may be returned to normal for the operation of a following car and also to prevent the current flowing through the solenoids 4 or 5 beyond a predetermined time as these solenoids are usually designed to operate under a high current for a short time and are, therefore, in danger of being injured by a prolonged application of current as would be the case if the collector

10 W should come to rest upon the pan P.

Therefore, I provide an electrically operated switch D provided with two controller coils 34 and 35. The coil 35 is normally energized due to its terminals being connected to the switch arm 18 by the conductor 26 and to the conductor 28 by the conductor 37 thereby its arm 18 is normally raised and held in engagement with the contact 19. The coil 34 has its terminals connected to the switch arm 18 through the conductor 36 and to the switch arm 12 through the conductor 38, therefore, the coil 34 is energized only when the switch arm 12 is energized through the closing of the switch C.

As soon as the switch arm 22 is closed upon its contact 23 and as there is practically no resistance between the trolley conductor 3 and the switch arm 18, the coil 35 will be practically short circuited on account of its terminals being connected to the switch arm 18 and to the conductor 28 leading to the trolley conductor, therefore, the coil 35 will be de-energized. Likewise the coil 38 will be short circuited after it is connected to the switch arm 12 and to the switch arm 18 and no current can flow therethrough while the switches C and D are closed, and the arm 12 in engagement with its contact 13. The de-energizing of the coil 35 and non-energizing of the coil 34 upon the closing of the switch C will permit the switch D to open and as soon as this occurs the short circuit is removed from the coils 34 and 35 and they will be energized, but they are wound for equal energizing capacity and connected in differential, therefore, they will maintain the switch D in an open position and will prevent current flowing through the conductor 17 and the solenoid 4. The switch D will not open immediately upon the de-energizing of the coil 35, but due to the residual magnetism therein and the relation of the arm 18 to the magnetic core of the coils 34 and 35, all of which is well known to those skilled in the art, a time lag is provided in the switch D hence the switch D will open after a predetermined time after the closing of the switch C, when the arm 12 engages the contact 13 as is the case when the collector engages the pan with "power off".

In order to open the circuit 15 leading to the solenoid 5 which will be closed when the collector engages the pan P with "power on", I make use of the coil 11 for this pur-

pose. It will be noted that the coil 11 is connected to the conductor 16 by the conductor 39 and is connected to the conductor 15 by the conductor 40, therefore, whenever the conductor 16 is energized, current will flow 70 through the coil 11 and out through the conductor 15 to ground through the solenoid 5. The coil 11, however, has its winding so proportioned that it will not be sufficiently energized to raise the arm 12, but if the arm 12 75 has been raised by the coil 10 the coil 11 will hold the arm in a raised position. It will also be evident that when the conductor 16 is energized it is due to the fact that the collector has engaged the pan P with "power off", therefore, the energizing of the coil 11 when the conductor 16 is energized has no effect upon the arm 12. If, however, the arm 12 has been raised due to the collector engaging the pan P with "power on" then 80 the coil 11 becomes a holding or stick coil and current will then flow through the coil up through the conductor 39 and from the conductor 16 through the solenoid 4 to ground. It will also be evident that as long 85 as the switch D remains closed that the coil 11 will be energized regardless of whether the collector is in engagement with the pan or has passed off the pan.

It will be noted that when the arm 12 engages the contact 14 and is energized that the coils 34 and 35 do not operate under a short circuit, but each coil is immediately energized, but in differential relation as soon 90 as the arm 22 engages the contact 23, and a time lag is also provided by this means against the switch D opening immediately. As soon as the switch D does open, however, the circuit by which the coil 11 is energized 95 will be broken and its holding effect become 100 nil and the arm 12 will return to its normal position in engagement with the contact 13. The switch 18, however, cannot close as long 105 as the arm 22 remains in engagement with the contact 23 and this engagement will take place as long as the collector is in contact 110 with the pan P or for a period of time after the collector has left the pan while the switch D remains closed.

The flow of current in the coil 11 is reversed, depending upon which the system is working, "power on" or "power off" the motors.

If in approaching the track switch the car operator desires to go "straight ahead", he will turn his controller to the "power off" position so as to pass over the pan P with his controller in the "power off" position. As soon as the collector engages the pan the 120 switch C will be operated to close the circuit through the solenoid 4 and the circuit at the contact 25 will be opened. The switch D will open after a predetermined time after the collector has engaged the pan P and 125 while still in engagement, providing the car 130

is moving sufficiently slow, but if the car is moving fast and the collector passes the pan P before the switch D opens, the switch 22 will be maintained closed on account of the holding coil 21 being energized until the switch D opens. If the car should come to rest for any reason with the collector in contact with the pan P and should later start up, the throwing of the controller to "power on" will not energize the coil 10 for the reason that its circuit is open at the contact 25 and the contact member 1 is deriving its current from the trolley conductor through the resistance R and its connections. From this it will be seen that the solenoids 4 and 5 are supplied with current for a predetermined time regardless of the position of the current collector after it has set the system in operation with "power off".

If the car operator desires to take the "curve" when he approaches the pan P, he will throw his controller to the "power on" position. In this case the coil 10 will be energized and the switch C operated and the arm 12 raised into engagement with the contact 14. The holding coil 11 comes into operation immediately and maintains the arm 12 in engagement with the contact 14 until the switch D opens after a predetermined time which may be while the collector is still in engagement with the pan or after it has passed beyond the pan. It will be noted that should the car for some very remote reason stop with its controller in engagement with the pan P after it has engaged it with "power on" and the switch D has opened, that the switch 12 will then drop back into engagement with the contact 13, but this cannot operate the track switch to the "straight ahead" position for the reason that the circuit through the solenoid 4 is open at the contact 19 and held open as long as the collector engages the pan P due to the energizing of the coil 20.

I claim:

1. In a switch operating system, the combination of a trolley conductor, a contact pan, an electrically operated track switch, a resistance connecting the conductor and the pan, a selector switch to direct the movement of the track switch and having controlling circuits thereto, an operating coil for the selector switch connected in shunt with the resistance and energized when the pan is engaged by a current collector with "power on" to operate the selector switch.
2. In a switch operating system, the combination of a trolley conductor, a contact pan, an electrically operated track switch, a resistance connecting the conductor and the pan, a selector switch to direct the movement of the track switch and having controlling circuits thereto, an operating coil for the selector switch connected in shunt with the resistance and energized when the pan is en-

gaged by a current collector with "power on" to operate the selector switch and means to open the circuit through the coil when the collector engages the pan.

3. In a switch operating system, the combination of a trolley conductor, a contact pan, an electrically operated track switch, a selector switch to direct the movement of the track switch and having controlling circuits thereto, an operating coil for the selector switch connected to the conductor and the pan and a shunt normally connected across the terminals of the coil to control the current flowing therethrough.

4. In a switch operating system, the combination of a trolley conductor, a contact pan, an electrically operated track switch, a selector switch to direct the movement of the track switch and having controlling circuits thereto, an operating coil for the selector switch connected to the conductor and the pan and a shunt across the terminals of the coil to control the current flowing therethrough and means to open the circuit through the coil.

5. In a switch operating system, the combination of a trolley conductor, a contact pan, an electrically operated track switch, a selector switch to direct the movement of the track switch and having controlling circuits thereto, an operating coil for the selector switch connected to the conductor and the pan, a shunt across the terminals of the coil to control the current flowing therethrough, means to open the circuit through the coil and close the controlling circuits to the track switch.

6. A switch operating system comprising in combination, an electrically operated track switch, operating circuits leading thereto, a selector switch controlling the operating circuits to direct the movement of the track switch, an operating coil for said selector switch, and a resistance across the terminals of said coil as described.

7. A switch operating system comprising in combination, an electrically operated track switch, operating circuits leading thereto, a selector switch controlling the operating circuits to direct the movement of the track switch, an operating coil for said selector switch, a resistance across the terminals of said coil as described, and normally closed means connecting the coil and resistance in shunt and operating to break said shunt when the selector switch has positioned said track switch.

8. A switch operating system comprising in combination, an electrically operated track switch, operating circuits leading thereto, a selector switch controlling the operating circuits to direct the movement of the track switch, an operating coil for said selector switch, a resistance across the terminals of said coil as described, normally

closed means connecting the coil and resistance in shunt and operating to break said shunt when the said coil has been energized and means to control said operating circuits 5 after a predetermined time after the operation of the track switch.

9. A switch operating system comprising in combination, an electrically operated track switch, operating circuits leading 10 thereto, a selector switch controlling the op-

erating circuits to direct the movement of the track switch, an operating coil for said selector switch, a resistance across the terminals of said coil as described, normally closed means connecting the coil and resistance in shunt and operating to break said shunt when the said coil has been energized and means to control said operating circuits. 15

In testimony whereof I affix my signature.
GEORGE A. MEAD.
